[57] CLAIM

The ornamental design for a jewelry link, as shown and described.

DESCRIPTION

FIG. 1 is a perspective view of a jewelry link showing my new design;

FIG. 2 is a top plan view;

FIG. 3 is a front elevational view;

FIG. 4 is a rear elevational view;

FIG. 5 is a bottom plan view;

FIG. 6 is a side elevational view;

FIG. 7 is a perspective view of a jewelry link showing a second embodiment of my new design;

FIG. 8 is a top plan view of FIG. 7;

FIG. 9 is a front elevational view of FIG. 7;

FIG. 10 is a rear elevational view of FIG. 7;

FIG. 11 is a front elevational view of FIG. 7; and,

FIG. 12 is a side elevational view of FIG. 7.

The broken line showing of adjacent links in FIGS. 2 and 8 are for illustrative purposes only and forms no part of the claimed design.
